at the

UNITED STATES PATENT OFFICE.

CURTIS W. HYMER, OF DETROIT, MICHIGAN, ASSIGNOR TO LARNED, CARTER & COMPANY, OF DETROIT, MICHIGAN, A CORPORATION OF MICHIGAN.

GARMENT.

1,121,367.

Specification of Letters Patent. Patented Dec. 15, 1914.

Application filed July 15, 1911. Serial No. 638,697.

To all whom it may concern:

- Be it known that I, CURTIS W. HYMER, a citizen of the United States of America, residing at Detroit, in the county of Wayne and State of Michigan, have invented certain new and useful Improvements in a Garment, of which the following is a specification, reference being had therein to the accompanying drawings.
- 10 The invention relates to garments and particularly to overalls, and it is the object of the invention to obtain an improved construction of reinforcement for the placket opening as more fully hereinafter set forth.
- 15 In the drawings,—Figure 1 is a front elevation of the portion of the garment to which my improvement is applied; Fig. 2 is an elevation viewed from the inside; Fig. 3 is a cross section on line $x-x$ Fig. 2.
- 20 A is the front flap and B the rear flap on opposite sides of the placket opening C of a garment such as a pair of overalls, D are buttons and E are the button holes securing these flaps together.
- 25 It is the particular object of the present invention to obtain a construction of reinforcement in which the reinforcing member is completely concealed when the garment is in use. This permits of employing for 30 the reinforcement member, scraps of material of inferior quality or even of different color without detracting from the appearance or saleability of the garment.
- 35 As shown, F is a separate piece of material which is stitched to the rear flap member B to reinforce the edge of the flap. This reinforcement member is arranged mainly on the under side of the garment as shown in Fig. 2, but is folded over to form 40 the edge of the placket extending on the outside over that portion only which is overlapped by the front placket A when the placket is closed. The reinforcement is secured by a line of stitching G along the 45 outer fold F' the edge of which is turned under at H. This outer fold extends downward below the juncture of the placket and for sufficient distance to prevent danger of tearing in case the user catches his foot in 50 the placket opening in drawing on the garment. The opposite fold of the reinforcement which is arranged on the inside of the garment extends for a greater distance from the placket opening and is secured by a line 55 of stitching I. This also preferably extends

beneath the point of securing of a pocket member J which imparts additional strength to the structure.

What I claim as my invention is:

1. In a garment, the combination with 60 front and rear flaps forming opposite sides of a placket, of a reinforcement for one of said flaps comprising a separate piece of material arranged mainly upon the inside of the garment and extending below the 65 point of juncture of the flaps, said reinforcement being folded to form the edge of the placket and extending outward over that portion which is overlapped by the opposite flap. 70
2. In a garment, the combination with front and rear flaps forming opposite sides of the placket, of a reinforcement for one of said flaps comprising a separate piece of material arranged mainly on the inside of 75 the garment and extending below the point of juncture of the flaps, said reinforcement being folded to overlap a portion of the outside of said flap, said overlapping portion being itself overlapped by the front flap 80 when the placket is closed, and placket closing means secured to the reinforcement. 85
3. In a garment, the combination with front and rear flaps forming the opposite sides of a placket, of a reinforcement for one of the flaps comprising a separate piece 90 of material folded to provide a relatively narrow front fold or portion and a rear fold or portion of a width substantially greater than the width of the said front fold, the relatively narrow front fold or portion having its free edge overlapping a portion on the outside of said flap, the rear fold or portion extending along the under side of the 95 said flap a substantial distance to one side of the edge thereof, the free marginal portions of the said folds being secured to the said flap by separate lines of stitching, said reinforcement being arranged mainly on the inside of the garment, the relatively narrow front fold or portion being overlapped and covered by the front flap when the placket is closed, and a pocket member secured to the outside of the said flap and overlapping a part of the rear fold of the reinforcement 100 on the inside of the garment. 105
4. In a garment, the combination with front and rear flaps forming the opposite sides of a placket, of a reinforcement for one of said flaps, comprising a separate piece of 110

material arranged mainly on the inside of the garment and extending considerably below the point of juncture of the flaps, said reinforcement having a portion folded to 5 overlap a portion on the outside of said flap and secured thereto, the other flap overlapping said last-mentioned portion when the flaps are closed, and a second reinforcing member extending from adjacent the point 10 of juncture of the placket flaps downward there below.

5. In a garment, the combination with front and rear flaps forming the opposite sides of a placket, of a reinforcement for 15 one of the flaps comprising a separate piece of material folded to provide a relatively narrow front fold or portion and a rear fold or portion of a width substantially greater than the width of the said front fold, the

relatively narrow front fold or portion having its free edge overlapping a portion on the outside of said flap, the rear fold or portion extending along the under side of the said flap a substantial distance to one side of the edge thereof, the free marginal portions of the said folds being secured to the said flap by separate lines of stitching, said reinforcement being arranged mainly on the inside of the garment, the relatively narrow front fold or portion being overlapped and covered by the front flap when the placket is closed. 20 25 30

In testimony whereof I affix my signature in presence of two witnesses.

CURTIS W. HYMER.
